[57] CLAIM

The ornamental design for an eating utensil, substantially as shown and described.

DESCRIPTION

FIG. 1 is a bottom plan view of an eating utensil, showing my new design as embodied in a fork;

FIG. 2 is a side elevational view thereof; the opposite side, not shown, is the mirror image thereof;

FIG. 3 is a top plan view thereof; and

FIG. 4 is an end elevational view thereof as seen from the right of FIG. 1.

FIG. 5 is a side elevational view of an eating utensil showing my new design as embodied in a knife;

FIG. 6 is a top plan view thereof;

FIG. 7 is a bottom plan view thereof;

FIG. 8 is a side elevational view thereof; and

FIG. 9 is an end elevational view thereof as seen from the right of FIG. 5.
